OGIVE MOUNTING MEANS FOR PROJECTILES

George W. Blackinton and John J. Calhoun,
Philadelphia, Pa., assignors to The Budd Com-
pany, Philadelphia, Pa., a corporation of Penn-
sylvania

Application November 21, 1942, Serial No. 466,395

1 Claim. (Cl. 102—56)

1

This invention relates to projectiles, more par-
ticularly to projectiles of the armor-piercing type
having a relatively long ogive.

In a copending application Serial No. 455,323,
filed August 19, 1942, we have described an or-
mor-piercing projectile of the rifle grenade type
which employs a cone shaped member projecting
into the charge, and a relatively long ogive. The
present invention is directed to projectiles of
large size or diameter such as are discharged
from a gun, and which employ a cone and rela-
tively long ogive for the same purpose as de-
scribed in said copending application.

The present invention is directed, in projectiles
of the above character, to an improved means for
mounting the cone and ogive which is so con-
structed as to facilitate the loading of the explo-
sive charge.

Accordingly, one of the objects of the present
invention is to provide a new and improved
means for connecting the ogive with the body of
the projectile.

Another object is to provide an ogive mounting
means of such construction that this means, with
the ogive removed, may be employed to support
the projectile or shell in an upright position to
facilitate the loading of the same with the explo-
sive charge, which means also securely holds
the cone-shaped member in position within the
body of the projectile.

With the above and other objects in view, the
present invention consists in certain features of
construction and combinations of parts to be
hereinafter described with reference to the ac-
companying drawing, and then claimed.

In the drawing which illustrates a suitable
embodiment of the invention,

Figure 1 is a longitudinal sectional view of the
projectile,

Figure 2 is a view similar to Figure 1 but with
the ogive removed, and

Figure 3 is a fragmentary sectional view of a
slightly modified mounting means.

In the accompanying drawing in which like
numerals refer to like parts throughout the
views, the numeral 10 indicates a projectile or
shell body having a receiving chamber 11 for the
explosive charge 12. The trailing end of the
chamber 11 is internally threaded at 13 to
threadedly receive the detonator housing 14. The
opposite or leading end of the chamber 11 is
counter-bored to provide a seat 15 and a wall
of enlarged diameter which is internally thread-
ed as indicated at 16. The cone member 17 is
formed with a circumferential flange 18 which as

2

shown in Figure 1 is seated against the shoulder
or seat 15.

In accordance with the present invention, the
cone member 17 is very rigidly held in place by
an annular ring 19 which is externally threaded
as indicated at 20 in Figure 2 and threadedly re-
ceived by the internal threads 16 to abut and se-
curely clamp the flange 18 against the seat 15.
A portion of the threaded portion of the ring 19
projects beyond the end of the shell body 10 for
threadedly receiving the ogive 21.

The ogive 21, as shown in the drawing, is of
conical shape and internally threaded so that it
can be threaded onto the projecting threaded
portion of the ring 19.

In loading the shell, the ogive 21 is removed
and the shell body 10 is disposed in an upright
position, as shown in Figure 2, the projecting
portion of the annular ring 20 serving as a sup-
porting base to maintain the body 10 in a rela-
tively stable upright position. The explosive
charge 12 may then be poured into the receiving
chamber 11 to the desired level, after which the
detonator housing 14 is threaded into position
and the seal 22 inserted and flattened as indicat-
ed at the right in Figure 1. The seal 22 is shown
at the left in Figure 1 in its unflattened condi-
tion. The ogive may then be threaded onto the
projecting portion of the ring 20.

The mounting means of the present invention
thus provides not only an efficient means for
mounting the ogive and clamping the cone in po-
sition but also provides a means for supporting
the shell during loading with the explosive
charge, thus eliminating the necessity of provid-
ing special jig fixtures for supporting the shells
during the loading operation.

The slightly modified construction of Figure 3
which is particularly adaptable for use when it
is desired to employ a standard diameter of cone
in shells of different internal diameters, that is a
cone in which the circumferential flange 18 is not
of sufficient diameter to engage the seat 15, em-
bodies an externally threaded spanner nut 23
which is threaded into the counter bore to en-
gage the seat 15. This nut is of such internal
diameter as to project radially inwardly beyond
the edge of the seat 15 and thus in itself provide
the seat for the flange 18 of the cone member 17.
Apart from this, the construction is the same as
shown in Figure 1, the externally threaded ring
19, in addition to providing the mount for the
ogive, also clamps the cone flange 18 against the
nut 23.

Obviously, various changes may be made in the

detailed construction and arrangement of parts without departing from the spirit and substance of the invention defined by the appended claim.

What is claimed is:

In a projectile, a hollow casing having open ends, one of said open ends having a counter-bore providing an annular shoulder therein, a conical member extending within said counter-bore and having a peripheral flange abutting said shoulder, an externally threaded annular ring 10 threadedly connected with the wall of said coun-

ter-bore and clamping said flange against said shoulder, said ring extending axially beyond said one open end, and a shell-like ogive having internal threads at one end, said internal threads having threaded engagement with the threads of said ring, said ring with the ogive removed providing means for supporting the casing in an upright position to permit loading thereof with an explosive charge through the opposite end.

GEORGE W. BLACKINTON.
JOHN J. CALHOUN.
